UNITED STATES PATENT OFFICE

RICHARD R. MEAD, OF QUEENS VILLAGE, NEW YORK, ASSIGNOR TO MERGENTHALER LINOTYPE COMPANY, A CORPORATION OF NEW YORK

TYPOGRAPHICAL MACHINE

Application filed June 26, 1930. Serial No. 463,896.

This invention relates to typographical machines, such as linotype machines of the general organization represented in Letters Patent of the United States No. 436,532 to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter elevated and returned through distributing mechanism to the magazine from which they started. More particularly, it relates to machines equipped with a plurality of magazines containing different matrix fonts and which are arranged to be moved upwardly and downwardly in the machine to bring one or another into operative relation to the assembling and distributing mechanisms.

In these machines, the magazines are mounted in such manner that they may be quickly removed and replaced by other magazines containing different matrix fonts, it being customary to apply to the base frame of the magazine to be removed a pair of supporting arms on which the magazine may slide forwardly when disengaged from its base frame.

It sometimes happens that the magazines are prematurely disengaged from their base frames, or improperly placed thereon, so that they slide off when the supporting arms are not in position to receive them; and in that case, the falling magazines are likely to cause considerable damage to themselves or to other portions of the machine, as well as injury to the operator. The present invention is therefore directed to certain improvements in machines of the class stated intended to lock the magazines in place and to prevent their release except when the supporting arms are in position to receive them. The construction and arrangement of the parts will best be understood from the detailed description which follows.

While as above stated, the invention is intended for use more particularly in machines

equipped with a plurality of shiftable magazines, it is also applicable to machines of the single magazine variety.

Referring to the drawings:

Figure 1 is a side elevation of a portion 55 of a linotype machine equipped with the invention;

Fig. 2 is a similar view on a larger scale, showing the front portions of the magazines with their base frames and associated parts, 60 and indicating how the magazines are removed;

Fig. 3 is a longitudinal sectional view on line 3—3 of Fig. 2; and

Fig. 4 is a fragmentary top plan view of 65 the new automatic lock at one side of the magazine.

The matrices are stored according to font in the superposed channeled magazines A, three of which are shown herein but of which a greater or less number might be employed if desired. The several magazines are removably supported upon separate base frames A¹ conjointly constituting a shift frame which is arranged to be moved upwardly and downwardly in the fixed machine frame in the well known manner to bring any selected magazine into operative relation to the assembling mechanism B at the lower end and the distributing mechanism 80 C at the upper end. Each of the magazines is provided with a series of matrix releasing escapements D (Fig. 2) which, when the magazine is brought into operative position, are actuated under the control of the keyboard mechanism in the usual way. 85

In the present instance, the two upper base frames A¹ are pivoted at their upper ends, as at A², to a pair of plates rising from the lowermost base frame, so that the base frames and their respective magazines may be separated or spread apart to permit the independent removal of any selected magazine. Such separation of the magazines may be effected by any suitable type of spreading mechanism A³, as for example that shown and described in the application of H. A. Southern, Serial No. 399,956, filed October 16, 1929, to which reference may be had for details if desired. When in use, the magazines 90

and base frames occupy the close parallel relation shown in Fig. 1, but when either the lower magazine or the intermediate magazine is to be removed, the spreading mechanism B will be actuated to cause the parts to occupy their spread apart relation.

In the embodiment illustrated the bank of escapements for each magazine is mounted in a fixed or set position upon the corresponding base frame, and means are provided for lifting the magazine from the base frame to disengage it from the escapement bank preparatory to its removal or replacement, such lifting means being preferably constructed to support the magazine in its elevated position and to guide it in a straight path as it is drawn forwardly from the front of the machine.

As best shown in Fig. 2, each bank of escapements D is mounted in the usual manner in a supporting bar of frame D¹, which frame is screwed or otherwise fastened to the lower end of the corresponding base frame A¹. As ordinarily, the magazines are formed on their undersides with transverse slots or openings to receive the escapement bars, the latter being formed on their upper sides with grooves which extend across the magazine openings and constitute in effect continuations of the grooves in the bottom plates of the magazines. Such being the relation of the parts, it is apparent that before a magazine can be removed, it must first be disengaged from its escapement bank.

For this reason, each base frame is provided with a central magazine lifting and supporting plate E, which in the present instance is substantially as long as the base frame itself and which is located in a corresponding groove or recess E¹ formed in the upper side of the base frame. At its upper end, the plate E is pivoted to the base frame in the usual way, thus permitting it to be swung upwardly in lifting the magazine; and at its lower end, it is provided with stop shoulders E² normally engaged with the customary forward transverse rib *a* on the underside of the magazine and which thus retain the magazine in place on the plate when the latter is in its raised position.

The swinging of the magazine lifting and supporting plate of each base frame is controlled and effected by a cam or equivalent device F arranged near the lower end thereof and fast to a transverse rock shaft F¹ journaled in the base frame. The cam F, when turned upwardly by rocking the shaft F¹, engages against the lower side of the plate E, lifting the same from the base frame to a position as indicated by dotted lines in Fig. 2, in which condition the magazine can easily be removed from the base frame. The cam is limited in its downward movement by a stop shoulder F² in the bottom of a recess F³

in the base frame and against which the cam rests in its lowered position.

The operation of the cam shafts F¹ may be effected in any desired manner, but it is proposed to employ for the purpose the usual magazine supporting arms G. As shown, these arms G are provided with bosses G¹ adapted to be applied to the opposite ends of the cam shaft F¹ of any selected base frame, means being provided, as will later be explained, for keying the arms to the selected cam shaft, so that the magazine supporting arms may be readily applied to or removed from the required cam shaft and, when applied, serve as handles or cranks for turning it in one direction or the other. In the operative position of the magazine supporting arms shown by the dotted lines in Fig. 2, they rest at their inner edges upon the opposite ends of the appropriate escapement bar D¹, the arms being provided with pins D² which enter corresponding apertures in the escapement bar and prevent their accidental disconnection from the cam shaft.

In removing a selected magazine, the supporting arms are applied to the corresponding cam shaft F¹ in a position substantially at right angles to the magazine and are then drawn downwardly to their magazine supporting position, which action effects the turning of the cam shaft and the lifting of the magazine from the base frame as just described. The magazine is then slightly raised at its forward end to disengage its front rib *a* from the stop shoulders E² and slid forwardly along the plate E onto the supporting arms, all as more fully described in the McNamara Patent No. 1,586,316.

Coming now to the present invention, it sometimes happens that the matrices protrude slightly from the forward ends of the magazines, and in shifting the base frames downwardly to bring a selected magazine into operative position, these projecting matrices come into engagement with portions of the assembling mechanism and arrest the downward movement of the particular magazine from which they protrude. When this happens, the continued downward movement of the corresponding base frame (which is not arrested) will result in the disengagement of the magazine rib *a* from the stop shoulders E² of the lifting plate, leaving the magazine free to slide forwardly and downwardly out of the machine. If this should occur at a time when the magazine supporting arms G are not in proper receiving position on the machine (and they never are during the movements of the shift frame), considerable damage is likely to be caused by the falling magazine. For this reason, it is proposed to lock the magazines in position upon their respective base frames so that they cannot be displaced therefrom except when the magazine supporting arms are in place. To this

end, the invention contemplates the application of locking means H at the opposite sides of the base frames, said locking means functioning normally to maintain the magazines upon their base frames.

In the present instance, the improved locking means is shown only in connection with the uppermost magazine (the one which is the chief offender), although it may of course be applied to all of the magazines if desired. As best shown in Figs. 3 and 4, the locking means is preferably located at each side of the base frame A^1 and comprises a supporting plate H^1 , secured to the base frame as by screws H^2 or other suitable fastening means, and a latch member H^3 pivoted to the plate H^1 as by a pin H^4 . The inner end of the latch member H^3 is provided with a small shoulder H^5 adapted to engage the adjacent edge of the lower plate of the magazine, and disposed between the latch member and the plate H^1 is a small compression spring H^6 which normally tends to disengage the latch member from the magazine. The outer end H^7 of the latch member extends toward the adjacent magazine supporting arm G and has a relatively flat bottom surface H^8 , at one side of which is a slight bevel H^9 .

Operative below the outer end H^7 of the latch member is a cam F^6 which may be integral with a collar F^7 secured to the shaft F^1 by a transverse pin F^8 . The collar and cam are mounted on the shaft at the outer side of the base frame and are provided with teeth or keys F^9 adapted to seat in grooves or keyways F^{10} formed on the inner face of the supporting arm boss G^1 . Thus, the collar F^7 with its teeth or keys F^9 constitutes the connection by virtue of which the attached arms G rock the shaft for raising and lowering the magazine supporting plate E .

The cam F^6 is provided with a high point F^{11} which is adapted alternately to engage and disengage the lower surface H^8 of the latch member in such manner that, as the shaft is rocked to lower the cam F , said high point F^{11} will act upon the outer end H^7 of the latch member and lock it in its engaging position with reference to the magazine.

When, however, the shaft is rocked in the opposite direction to swing the cam F upwardly and thereby to raise the magazine lifting plate E , the cam F^6 will release the latch member, leaving it free to be swung into its disengaged position by the compression spring H^6 . The shaft F^1 will, of course, only be rotated by the magazine supporting arms G , and therefore it will be clear that the locking means is under the control of the magazine lifting means and can not be released until the supporting arms are swung downward into position for receiving the magazine from the base frame.

It is believed that the operation of the parts will be entirely clear from the foregoing

description. However, to recapitulate, it may be stated that under normal conditions of operation, the magazines and their base frames are in the closely nested relation shown in Fig. 1 with the selected magazine 70 in operative position with reference to the assembling mechanism B . In this condition, the lifting cams F are in their lowermost positions within the base frame recesses F^5 , and the cams F^6 are in their locking positions, 75 maintaining the latch members H^3 in engagement with the opposite edges of the magazine, and thus firmly holding the magazine on its base frame. If, now, it is desired to remove the upper magazine A (assuming it to be in 80 position for removal as it is in Fig. 1), the magazine supporting arms G are applied to the ends of the shaft F^1 , as shown by the full lines in Figs. 2 and 3, and are then swung downwardly to the dotted line position indicated in Fig. 2, thereby rocking the shaft. In the initial movement of the shaft, the cams F^6 disengage the latch members H^3 to release the magazine from its base frame, and thereafter the continued movement of the 90 shaft causes the cam F to swing the plate E upwardly, lifting the magazine to disengage it from the escapements. The magazine is then free to be slid forwardly onto the supporting arms and removed in the customary way. In substituting a new magazine, the above operations are simply reversed, that is to say, after sliding the new magazine back onto the lifting and supporting plate E , the supporting arms G are 95 thrown upwardly to lower the magazine into engagement with the escapements, and in the final movement of the rock shaft F^1 , the cams F^6 act against the lower surfaces H^9 and H^8 to move the latch member H^3 into 100 their locking positions.

In the accompanying drawings, the invention has been shown merely in preferred form and by way of example and as applied to a machine of the class stated, but obviously many modifications and alterations may be made therein without departing from the spirit of the invention. For instance, the invention in its broader aspects is not limited to machines in which the magazine must first be disengaged from its escapement bank before removal, but is also applicable to machines in which the escapements are carried by the magazine. Moreover, the invention does not require that the release of the magazine latches be effected by a rotary movement of the magazine supporting arms after their attachment to the base frame, but contemplates as well the release of the magazine latches by the direct application of the magazine supporting arms to the base frame. These and other changes will readily suggest themselves to those skilled in the art, and it should therefore be understood that the invention is not limited to any specific form or 115 120 125 130

embodiment except in so far as such limitations are specified in the appended claims.

Having thus described my invention, what I claim is:

- 5 1. In a typographical machine, the combination of a matrix magazine, a base frame upon which it is removably supported, a magazine supporting member adapted to be applied to the base frame in position to receive the magazine therefrom preparatory to its removal or replacement, and means for locking the magazine in position on the base frame, said locking means being under the control of said magazine supporting member.
- 10 2. In a typographical machine, the combination of a matrix magazine, a base frame upon which it is removably supported, a pair of magazine supporting arms adapted to be applied to the base frame at opposite sides thereof in position to receive the magazine therefrom preparatory to its removal or replacement, locking means for maintaining the magazine in position on the base frame, and means to prevent the release of said locking means except when the supporting arms are moved into proper receiving position.
- 15 3. In a typographical machine, the combination of a matrix magazine, a base frame upon which it is removably supported, a bank of escapements mounted upon the base frame in operative engagement with the magazine, a magazine lifting and supporting plate pivoted to the base frame and adapted to be swung upwardly to disengage the magazine from the escapement bank preparatory to its removal or replacement, magazine supporting arms adapted to be applied to the opposite sides of the machine in position to receive the magazine from the base frame, locking means for maintaining the magazine in position on the base frame, and means for automatically releasing said locking means when the magazine supporting arms are in proper receiving position.
- 20 4. In a typographical machine, the combination of a matrix magazine, a base frame upon which it is removably supported, a bank of escapements mounted upon the base frame in operative engagement with the magazine, a magazine lifting and supporting plate pivoted to the base frame and adapted to be swung upwardly to disengage the magazine from the escapement bank preparatory to its removal or replacement, magazine supporting arms adapted to be applied to the opposite sides of the machine in position to receive the magazine from the base frame, locking means for maintaining the magazine in position on the base frame, and means to prevent the release of said locking means except when the magazine supporting arms are moved into proper receiving position.
- 25 5. In a typographical machine, the combination of a matrix magazine, a base frame upon which it is removably supported, a bank of escapements mounted upon the base frame in operative engagement with the magazine, a magazine lifting and supporting plate pivoted to the base frame and adapted to be swung upwardly to disengage the magazine from the escapement bank preparatory to its removal or replacement, magazine supporting arms adapted to be applied to the opposite sides of the machine in position to receive the magazine from the base frame, locking means for maintaining the magazine in position on the base frame, and means to prevent the release of said locking means except when the magazine supporting arms are moved into proper receiving position.
- 30 6. In a typographical machine, the combination of a matrix magazine, a base frame upon which it is removably supported, a bank of escapements mounted upon the base frame in operative engagement with the magazine, a magazine lifting and supporting plate pivoted to the base frame near the upper end thereof, a rock shaft journaled in the base frame near the lower end thereof, a cam fast to said rock shaft and arranged to engage the lower end of the magazine lifting and supporting plate, a pair of magazine supporting arms adapted to be applied to the opposite ends of said cam shaft for rotating it to effect the upward swinging of the magazine lifting and supporting plate, pivoted latch members mounted on the opposite sides of the base frame for engaging portions of the magazine to lock the same in position, and cams secured to the rock shaft and adapted to move the latch members into locking position when the magazine lifting and supporting plate is lowered.
- 35 7. In a typographical machine, the combination of a matrix magazine, a base frame upon which it is removably supported, means including a rock shaft for raising and lowering the magazine out of and into operative position, magazine supporting arms adapted to be applied to the opposite ends of the rock shaft for actuating the same and adapted to receive the magazine from the base frame preparatory to its removal or replacement, latch members arranged at opposite sides of the base frame and adapted to engage portions of the magazine to maintain it normally in position, and means associated with the rock shaft for releasing said latch members only when the magazine supporting arms are moved into proper receiving position.
- 40 8. In a typographical machine, the combination of a plurality of matrix magazines, a shift frame therefor comprising a plurality of base frames upon which the respective magazines are removably supported, individual magazine lifting and supporting means

associated with the base frames and adapted to swing the corresponding magazines upwardly preparatory to their removal or replacement, magazine supporting arms adapted to be applied to the opposite sides of a selected base frame to receive the magazine therefrom, and locking means for normally maintaining the magazine on its base frame, said locking means being releasable only when the magazine supporting arms are moved into proper receiving position.

9. In a typographical machine, the combination of a plurality of matrix magazines, a shift frame therefor comprising a plurality of base frames upon which the respective magazines are removably supported, escapement banks mounted upon the respective base frames in operative engagement with the magazines, means including a rock shaft associated with each base frame and adapted to raise the respective magazines out of engagement with the escapement banks preparatory to the removal or replacement of the magazines, magazine supporting arms adapted to be applied to the opposite ends of the rock shaft of a selected magazine for actuating said shaft, locking means for normally maintaining the magazine in position on its base frame, and means for automatically releasing said locking means when the supporting arms are placed in magazine-receiving position.

10. In a typographical machine, the combination of a plurality of matrix magazines, a shift frame therefor comprising a plurality of base frames upon which the respective magazines are removably supported, escapement banks mounted upon the respective base frames in operative engagement with the magazines, a magazine lifting and supporting plate pivoted to each base frame near the upper end thereof, a rock shaft journaled in each base frame near the lower end thereof, a cam fast to each such rock shaft and arranged to engage the lower end of the associated magazine lifting and supporting plate, magazine supporting arms adapted to be applied to the opposite ends of a selected one of the rock shafts to actuate the same and to receive the corresponding magazine from its base frame, latch members pivoted to the opposite sides of said base frame and adapted to engage the magazine to maintain it in position, and means associated with the rock shaft for controlling the latch members when the magazine supporting arms are in proper receiving position.

In testimony whereof, this specification has been duly signed by:

60 RICHARD R. MEAD.
